UNITED STATES PATENT OFFICE

EARL R. SWANSON, OF CHICAGO, ILLINOIS, ASSIGNOR TO CHICAGO-CLEVELAND CAR ROOFING COMPANY, OF CHICAGO, ILLINOIS, A CORPORATION OF DELAWARE

RAILWAY CAR

Application filed May 27, 1929. Serial No. 386,401.

My invention relates to railway cars and more particularly to a load lifting device adapted to be associated with the roof structure.

5 A principal object of the invention is to provide means extending longitudinally of the car and supported by the roof structure affording means for receiving a rope, chain or other hoist device whereby automobiles and similar objects may be raised above the car floor.

10 A primary feature of the invention consists in providing a car roof of the type involving carlines and roof sheets, with a beam member 15 extending longitudinally of the car which is connected to the carlines by a plurality of brackets, and in associating therewith, members which respectively extend substantially continuously between the carlines in spaced 20 relation to the beam member for supporting the roof sheets.

15 Another feature of the invention resides in constructing a car roof of the type involving carlines and roof sheets, with a beam member 25 extending longitudinally of the car and connected to the carlines in spaced relation to the roof sheets, roof sheet supporting members being interposed between each of the roof sheets and beam member, each of said 30 supporting members being secured at its opposite ends to the beam member and being spaced from the latter intermediate its ends and extending substantially continuously between adjacent carlines.

35 Other and more specific features residing in advantageous forms, combinations and relations of parts will hereinafter appear and be pointed out in the claims.

40 In the drawings illustrating preferred embodiments of the invention,

Figure 1 is a longitudinal sectional view of a car roof embodying the invention.

45 Figure 2 is a fragmentary transverse sectional view of the construction illustrated in Figure 1.

Figure 3 is an enlarged detail view of a portion of the roof construction adjacent the carline illustrated in Figure 1.

50 Figure 4 is an enlarged detail view taken

at right angles to Figure 3, the roof sheets and associated seam cap being omitted.

Figure 5 is a view corresponding to Figure 1 illustrating a modified form of the invention.

55 Figures 6, 7 and 8 are respectively views corresponding to Figures 2, 3 and 4 illustrating the modified form of the invention shown in Figure 5.

Figure 9 is a top plan view of one of the carlines adjacent its central portion thereof employed in the modified form of the invention.

60 As the construction of the roof on opposite sides of its longitudinal center is identical, the transverse sectional views illustrated in Figures 2 and 6 depict only a little more than one half of the roof structure. Since the construction of the main elements of the roof structure illustrated in Figures 1 to 4, 65 inclusive, is the same as those illustrated in Figures 5 to 9, inclusive, with the exception of certain features of construction which will be hereinafter pointed out, corresponding parts of these two groups of figures will 70 be designated by similar reference numerals.

Referring more particularly to the drawings, 1 indicates one of the side plates of the roof structure having substantially vertical flanges 2 and 3, respectively connected by a 80 horizontal web 4. The end plates 5 of the roof, which, as is well known, are rigidly connected to the side plates, may also be advantageously of Z-section having similarly arranged flanges 6 and 7 and an intermediate 85 connecting web 8.

Extending from one side of the car to the other are carlines 9 which are preferably connected to the adjoining side plates 1 by brackets 10. Each of the carlines is of inverted channel shape having a substantially horizontal web 11 and downwardly projecting substantially vertical sides 12, respectively terminating in lateral base flanges 13. The roof sheets 14 which also extend continuously from one eaves edge of the roof to the other span the spaces between adjacent carlines. With the exception of the outer edges of the end roof sheets, the lateral edges of each are fashioned with upturned flanges 15 100

arranged in spaced relation to the adjacent sides of adjoining carlines. The outer edges of the end roof sheets may conveniently be flanged downwardly as at 16 for attachment to the adjoining end plates.

5 The edges of adjacent roof sheets are connected by seam caps 17, respectively embracing the carlines. The sides of each of the seam caps are offset as at 18 to form housings for the upturned flanges 15 of the roof sheets. The eaves edges of the roof sheets are preferably flanged inwardly as at 19 to cooperate with flashing strips 20 secured in any suitable manner to side fascias 21 which are respectively carried by the side plates 1. 10 The ends of the seam caps may be fashioned with downturned flanges 22 so that they may be readily secured to the side members of the roof by bolts 23. Intermediate their ends the seam caps may be firmly secured to the carlines by any suitable means, not shown.

15 The load lifting device 24, illustrated in the present embodiments of the invention as a T-beam, extends longitudinally of the car substantially midway between the ends of the carlines in spaced relation to the roof sheets. The beam is preferably connected at its ends to the flanges 6 of the end plates by brackets 25. In the form of the invention illustrated in Figures 1 to 4, inclusive, the beam member is connected to each of the carlines by angularly shaped brackets 26. Each of these brackets is formed with a central substantially horizontal web 27 adapted to underlie and be rigidly secured by a bolt 28 to the web 11 of the associated carline. Offset downwardly from and spaced laterally of the web 27 each bracket is provided with substantially horizontal portions 29 affording means to which the beam member may be attached. This connection between the brackets and beam members may be obtained by rivets 30 which respectively pass through the portions 29 of the brackets and the flange 31 of the beam. The horizontal portions 29 of each bracket are connected to the web thereof by legs or intermediate portions 32 which are respectively preferably disposed contiguous to and parallel with the sides 12 of the carline. Thus, it will be seen that the brackets generally have the same contour as the carlines. By forming the brackets in this manner and firmly attaching them to the carlines and beam it will be appreciated that the latter is rigidly supported in spaced relation to the roof sheets so that sufficient clearance is provided between it and the sheets to permit a chain, rope or other hoisting device to pass therebetween and be supported by the beam.

20 In the form of the invention illustrated in Figures 5 to 9, inclusive, the lateral base flanges of the carlines adjacent the central portions thereof are bent downwardly so as to lie in the respective planes of the sides 12

of the carlines, thereby forming downwardly projecting extensions 33 to which angularly shaped brackets 34 may be attached. These brackets are preferably arranged in pairs and each is formed with an upright portion adapted to be rigidly secured by a rivet 35 to one of the extensions 33 of the associated carline and with a horizontal portion 36 adapted to be secured by a bolt 37 to the flange 31 of the beam. The brackets of each pair are arranged so that the horizontal portions 36 thereof project in opposite directions laterally of the associated carline. By bending the lateral base flanges of the carlines adjacent their central portions so that they merge into the planes of the sides of the carlines it will be seen that convenient means is provided to which the beam supporting brackets may be secured and that the beam is supported in spaced relation to the roof sheets so that sufficient clearance is provided between it and the sheets to permit a chain, rope or other hoisting device to be readily supported thereby.

25 Adjacent the beam each of the roof sheets is preferably supported by a member 38 which extends continuously between adjacent carlines for substantially the entire width of the roof sheets. The main body portion 39 of each of these roof sheet supporting members is arranged in spaced relation to the beam and at their opposite ends each is provided with downwardly projecting substantially upright legs 40 which terminate in horizontal flanges 41. The flanges 41 in the form of the invention illustrated in Figures 1 to 4, inclusive of the drawings are preferably interposed between the portions 29 of the brackets and the flange 31 of the beam, resting upon the latter and being conveniently secured by the rivets 30 employed for connecting the beam to the brackets. The upright portions 40 of each of the roof sheet supporting members may be rigidified by a corrugation 42 and the upper surface of the main body portion 39 of each is preferably curved to insure a line contact between it and the associated roof sheets. The outer ends of the end roof sheet supporting members may be conveniently supported by angle brackets 43 secured to the respective end plates.

30 The roof sheet supporting members illustrated in Figures 5 to 9, inclusive, of the drawings, are formed similarly to those illustrated in Figures 1 to 4, inclusive. Instead of interposing the flanges 41 of the sheet supporting members between the brackets and beam member they may, if desired, as shown in Figures 5 to 9, inclusive, overlappingly engage the horizontal portions 36 of the brackets and be secured in place by rivets 37 heretofore described.

35 The portions of the roof sheets intermediate the ridge and eaves of the roof are supported by the usual purlins 44 which are connected to the carlines by bolts 45.

From the foregoing it will be perceived that not only is the roof structure provided with a strong and efficient means for cooperating with a hoist device such as a chain or 5 rope, but that means is also provided for conveniently supporting the sheets of the roof adjacent the ridge thereof.

I claim:

1. In a roof for railway cars, the combination 10 with a plurality of carlines, of roof sheets respectively associated with and spanning the spaces between the carlines, a beam member extending longitudinally of the car in spaced relation to the roof sheets, brackets connecting the beam member and carlines, and a plurality of roof sheet supporting members, each of said members having a plate-like portion spaced above the beam in engagement with the underside of the associated 15 roof sheet and being provided with downwardly offset portions rigidly secured to adjacent brackets.

2. In a roof for railway cars, the combination 20 with a plurality of carlines, of roof sheets respectively associated with and spanning the spaces between the carlines, a beam member extending longitudinally of the car in spaced relation to the roof sheets, means connecting the beam member and carlines, and members 25 respectively extending substantially continuously between said carlines for supporting said roof sheets, each of said members having a plate-like portion spaced above the beam in engagement with the underside of the associated 30 roof sheet and being provided adjacent its ends with downwardly offset portions rigidly secured to the beam.

3. In a roof for railway cars, the combination 35 with a plurality of carlines, of roof sheets respectively associated with and spanning the spaces between the carlines, a beam member extending longitudinally of the car in spaced relation to the roof sheets, means connecting the beam to said carlines, and 40 roof sheet supporting members respectively extending substantially the entire width of the roof sheets, said members being respectively interposed between the roof sheets and beam and each being provided with an intermediate portion spaced above the beam and with downwardly offset end portions rigidly secured to the latter.

4. In a roof for railway cars, the combination 45 with a plurality of carlines, of roof sheets respectively associated with and spanning the spaces between the carlines, a beam member extending longitudinally of the car in spaced relation to the roof sheets, said 50 beam having a substantially horizontal top flange, means connecting said beam and carlines, and a roof sheet supporting member interposed between each of the roof sheets and the beam, each of said supporting members 55 being provided with oppositely projecting

substantially horizontal end portions rigidly secured to said flange of the beam member and with an intermediate portion spaced above the latter and in engagement with the associated roof sheet, said members respectively 60 extending substantially continuously between adjacent carlines. 70

5. In a roof for railway cars, the combination 75 with a plurality of carlines, of roof sheets respectively associated with and spanning the spaces between the carlines, a beam member extending longitudinally of the car in spaced relation to the roof sheets, means connecting said beam member to the carlines, roof sheets supporting members respectively interposed between the roof sheets and beam member, each of said supporting members having substantially vertical legs at its opposite ends terminating in portions adapted to be rigidly 80 secured to said beam member. 85

6. In a roof for railway cars, the combination 90 with a plurality of carlines, of roof sheets respectively associated with and spanning the spaces between the carlines, a beam extending longitudinally of the car in spaced relation to the roof sheets, said beam having a vertical portion and a substantially horizontal top flange, brackets respectively connecting said beam and carlines, roof sheet supporting members respectively interposed 95 between the roof sheets and beam, each of said members being provided with portions arranged in overlapping relation with portions of adjacent brackets and having an upwardly offset intermediate portion spaced 100 above the beam in engagement with the underside of the associated roof sheets and means passing through the top flange of the beam for respectively rigidly securing the overlapping portions of the brackets and roof 105 sheet supporting members thereto.

7. In a roof for railway cars, the combination 110 with a plurality of carlines, of roof sheets respectively associated with and spanning the spaces between the carlines, a beam member extending longitudinally of the car in spaced relation to the roof sheets, brackets respectively connecting the beam member to the carlines, each of said brackets having a substantially horizontal flange secured 115 to the beam, roof sheet supporting members respectively extending substantially continuously from a bracket associated with one carline to a bracket associated with the next adjacent carline, said roof sheet supporting 120 members being spaced from said beam for the major portion of their length and each being provided with end portions arranged in overlapping engagement with the horizontal flanges of adjacent brackets, and means for 125 respectively securing the overlapping portions of said brackets and roof sheet supporting members to the beam.

8. In a roof for railway cars, the combination 130 with a plurality of carlines, of roof

- sheets respectively associated with and spanning the spaces between the carlines, a beam member extending longitudinally of the car in spaced relation to the roof sheets, means connecting said beam member to the carlines, roof sheet supporting members respectively interposed between the roof sheets and beam member, each of said supporting members having an intermediate portion spaced above
- 10 the beam in engagement with the associated roof sheet, said intermediate portion having downwardly extending legs terminating in angularly disposed portions rigidly secured to the beam.
- 15 9. In a roof for railway cars, the combination with a plurality of carlines, of roof sheets respectively associated with and spanning the spaces between the carlines, a beam member extending longitudinally of the car
- 20 in spaced relation to the roof sheets, means connecting said beam member to the carlines, roof sheet supporting member respectively interposed between the roof sheets and beam member, each of said supporting members
- 25 having a portion spaced above the beam in engagement with the undersides of the associated roof sheet, said roof sheet engaging portion being provided adjacent its ends with downwardly extending portions terminating in substantially horizontal flanges rigidly secured to the beam.

In testimony whereof I affix my signature.
EARL R. SWANSON.
